UNITED STATES PATENT OFFICE.

CURT W. HAGSTROM, OF WILMETTE, ILLINOIS.

FOLDABLE BATHTUB.

1,327,866.

Specification of Letters Patent. Patented Jan. 13, 1920.

Application filed February 20, 1918. Serial No. 218,183.

To all whom it may concern:

Be it known that I, CURT W. HAGSTROM, a subject of the King of Sweden, residing at Wilmette, county of Cook, and State of Illinois, have invented certain new and useful Improvements in Foldable Bathtubs, of which the following is a specification.

This invention relates to improvements in foldable bath tubs, especially intended for the bathing of infants and children, but also adapted to be used as laundry tubs and the like.

An object of the invention is to provide a collapsible trough made of waterproof fabric, canvas or the like, and to support this waterproof trough or tub at a suitable height from the floor on pivotally interconnected legs.

Another object of the invention is to provide in combination with a collapsible tub of waterproof fabric reinforcing members for top edges of the tub, said reinforcing members serving to maintain the top edges in straight condition, permitting however to fold the tub when the same is emptied.

Another object of the invention is to provide, in combination with a marginal flap near a top edge of the tub, elements connected with said flap and adapted to embrace the reinforcing members, so as to connect detachably the top edges straight to said articulated reinforcing members.

Another object of the invention is to provide in combination with a pair of links constituting a reinforcing member, means which permit the pivotal movement of the inner ends of both of said links in upward direction, preventing, however, the movement of these links in downward direction so as to render a collapse of the tub, owing to the weight of the water poured into the same, impossible.

Another object of the invention is to combine with a flexible trough transverse members to which edge portions of the trough are secured, and legs extending from said transverse members, said legs being removable from the transverse supporting members so as to permit the positioning of the flexible trough on the top of a larger tub or the like.

Another object of the invention is to provide in combination with a collapsible bath tub, a movable platform, preferably also made of flexible fibrous material and adapted to be stretched from one edge of the bath

tub to the opposite edge thereof, so as to constitute a support for the child while the same is being dressed.

It is furthermore an object of the invention to combine with the flexible bath tub a support for the flexible platform, said support including means for unwinding the flexible platform from a spool or drum provided for this purpose and for fastening said platform after it has been placed in operative position to cover the tub.

With these and other objects in view an embodiment of the invention is described in the following specification and is illustrated in the accompanying drawings, wherein—

Figure 1 is a perspective view of a flexible tube of this character supported by a collapsible frame work of the character of a camp chair or the like;

Fig. 2 is a top plan view of the same;

Fig. 3 is a perspective view of the flexible tub supported by an ordinary bath tub, the flexible tub being covered by a flexible platform stretched over the same;

Fig. 4 is a vertical section through the flexible tub;

Fig. 5 is a perspective detail section of a clip attached to a flap of the tub for connecting the same with the reinforcing bars of the upper ends;

Fig. 6 illustrates the adjoining ends of reinforcing links for the upper edge, in stretched condition;

Fig. 7 is a similar view of the said links in partly collapsed condition;

Fig. 8 is a top plan view of a portion of one of the legs permitting the establishment of a pivotal connection with another leg;

Fig. 9 shows another leg portion adapted for insertion into the portion illustrated in Fig. 8.

The tub 1 preferably consists of a piece of fabric which constitutes the end walls 2 and 3 and the bottom 4, which last named portion may be reinforced by additional plies of the fabric, if desired. The lateral edges of this fabric are connected with other pieces of fabric, which form the side walls 5 and 6 of the tub.

The two transverse edges of the fabric which constitutes the bottom and end walls 2, 3 and 4 are detachably fastened to transverse rods 7 and 8, as, for instance, by means of keyhole and pin connection, the transverse members 7 and 8 being equipped with a plurality of aligned projecting pins 10

adapted to be inserted into the wider portions of the keyhole shaped eyelets 11 near the transverse edges of the fabric. If the tub is filled with water the fabric will be stretched so that the narrow portions of the keyhole parts 11 will be held in engagement with the stems of the projecting pins 10. The central portion of the main fabric of the tub is provided with a nipple 12 which is firmly secured thereto and which on the outer surface of the tub is connected with a cock 13. A hose 14 may be attached to this cock so that the entire tub can readily be drained, if desired.

15 The longitudinal edges of the side walls 5 and 6 of the tub are held extended in the position shown in Fig. 1 by means of reinforcing members. Each of these members comprises a pair of pivotally interconnected links 15, 16, formed of bars which at their outer ends are bent into rings 17 loosely surrounding the transverse rods 7 and 8. Close to the rings 17 said links are twisted ninety degrees, as indicated at 18, so as to present their main portions in vertical planes adjacent to the outer surfaces of the side walls 5 and 6. The adjoining ends of the links 15, 16 are pivotally interconnected, as may be seen from Figs. 6 and 7. The 20 link 15 is provided near its free end with a short bar 19 fastened to the link by the rivets 20 and slightly offset from the plane of the link. Two pins 25 are secured in serial alignment between said link and short bar 19. The other link 16 has at its free end a notch 21 and a finger 22 projecting beyond the lower edge of the link, so that in stretched condition of the reinforcing member (Fig. 6) the longer portion 22 of the 25 link 16 rests on both of said pins, preventing thereby a folding of these two links in downward direction. A relative pivotal movement of the links 15, 16 in upward direction, however, is rendered possible, as a pivot pin 23 secured to the link 15 and bar 18 extends through a slot 24 of the other link 16. If force is applied from below upwardly against the two adjoining ends of the two links, they will both turn about the 30 transverse members 7, 8 and also slide relatively to each other the pin 23 being guided in the slot 24. The entire tub may thus be folded transversely and the two rods 7, 8 of the support may be brought quite close to each other.

35 The upper edges of the lateral walls 5, 6 of the tub are provided with overhanging flaps 25' which project above the reinforcing members 15, 16 and which are equipped at their inner surface with holding elements, like wire clips 26 sewed to the same and adapted to embrace the reinforcing members. The tub is therefore not only directly supported by the transverse members 7, 8 of the camp chair frame but also by the rein-

forcing links 15, 16 which connect the said transverse members.

The transverse rod 8 is provided near its ends with openings (not shown) into which the tenons 27 of legs 28 may be removably inserted. The legs 28 extending from member 8 intersect the legs 29 extending from the other transverse member, as shown. For the purpose of permitting a pivotal adjustment of the intersecting legs 28, 29 with respect to each other, one of said legs is provided with a pin, as, for instance, the stem of a wood-screw 30, the head 31 at a certain distance from the adjacent surface of the leg. The head 31 of this pin is provided with flattened portions 32; the opposite leg is provided with a striker plate 33 having a slot 34 to permit the passage of the head 31 through the striker plate 33 provided this head is presented to said slot 34 in a predetermined registering position. After the head 31 has been introduced into said slot 34 the two legs may be turned with respect to each other, so as to prevent the head from leaving the slot.

40 A yielding foldable platform permitting the placing of a child or clothes thereon while the child is being dressed is combined with the foldable tub. A roller 51 is rotatably supported by means of brackets 52 transversely near one of the transverse members 7 or 8 and attached to said roller is a curtain 50, which upon unwinding from said roller may be stretched across the tub. The free end of the curtain 50 may then 45 be fastened, as shown in Fig. 3 to the opposite transverse member, as by a strap 53 or the like. The roller 51, supporting the yielding platform 50, may either be of a construction similar to the known "shade 50 rollers" so as to automatically rewind the yielding platform when the free end of the same is released from attachment to the transverse member, or a crank 54 may be secured to said roller so as to facilitate the 55 rewinding while the unwinding can easily be effected by pulling at the free edge of the curtain.

45 I claim:

1. In a foldable tub, the combination of 50 a fabric, a pair of rods supporting the transverse edges of the fabric, legs extending from each rod, plates mounted on the legs extending from one of these rods, said plates being provided with a slot, and the 55 legs being provided with a circular recess in the rear of the slot, the legs extending from the other transverse supporting rod being provided with a pin having a head with flattened portions adapted for insertion through said slot into the circular recess in the other legs.

2. In a foldable tub, the combination of 60 a fabric forming the end walls and bottom of the tub, fabrics forming the side 65

walls thereof, a pair of links near the top edges of said side walls, one of said links being provided with a slot, and the other link having a pin passing through said slot,
5 said last named link being provided with a pair of pins in longitudinal alinement on said link, and the first named link being provided with a projection overlying both of said pins, when said two links are in
10 condition of alinement.

3. In combination with a foldable tub, a fabric forming the end walls and bottom

of the tub, foldable side walls, reinforcing members for said side walls near the top edges of the same, flaps on said side walls 15 overlying said reinforcing members, and clips secured to said flaps and embracing said reinforcing members.

In testimony whereof I affix my signature in the presence of two witnesses.

CURT W. HAGSTROM.
